UNITED STATES PATENT OFFICE.

ALFRED A. ZIEGLER, OF BOSTON, MASSACHUSETTS.

BONDING DEVICE FOR RAILS.

1,185,750.

Specification of Letters Patent. Patented June 6, 1916.

Application filed June 23, 1913. Serial No. 775,278.

To all whom it may concern:

Be it known that I, ALFRED A. ZIEGLER, a citizen of the United States, residing at Boston, in the county of Suffolk and State of Massachusetts, have invented an Improvement in Bonding Devices for Rails, of which the following is a specification.

This invention relates to bonding-devices for rails. It is common practice to attach 10 the ends of the bond-wires to the rails in such manner as to form large loops which extend over the tie-plates. These loops are unsupported between their ends and are very objectionable on account of the liability of breakage, as in such event the signal circuit is disrupted. Heretofore means 15 have been devised for supporting the bond-wire loops between their ends, but either the loops are concealed for a substantial portion of their length and hence do not 20 admit of immediate inspection, or they are connected with the tie-plate or with the attaching-means for the tie-plate in such manner as to interfere therewith and cause 25 trouble, particularly between the men who have charge of the track, and the men who have charge of the signal-system, and, so far as I am aware no support for a bond-wire loop has ever been adopted.

30 This invention has for its object the construction of an improved form of support for a bond-wire loop which is adapted to be arranged on the attaching-bolt of the tie-plate and to be held by said bolt regardless 35 of whether said bolt is tight or loose, said support being constructed and arranged so as to receive the bond-wire in such manner as to hold it, and also to admit of its removal and of its replacement without interfering with the attaching-bolt, and also to 40 admit of its immediate inspection throughout its length.

Figure 1 is a front elevation of a bonding-device for rails having supports for the 45 bond-wire loops embodying this invention. Fig. 2 is an enlarged horizontal section of the bonding-device, one of the supports being represented in plan view. Fig. 3 is an enlarged transverse vertical section showing 50 one of the supports in side elevation, and, Fig. 4 is an enlarged perspective view of the support removed from the attaching-bolt.

55 10, 10, represent the adjacent end-portions of two rails; 12, 12, the tie-plate; 15 the attaching-bolts for the tie-plate and 20 the bond-wires, all of which are or may be of

any usual or suitable construction. The bond-wire support embodying this invention consists essentially of an annular plate 25, adapted to be arranged on the shank of the 60 attaching-bolt and beneath the head of said bolt, thereby to occupy a position between the head of the bolt and the tie-plate. Said annular plate has an elongated or oval-shaped hole through it, which corresponds 65 in shape and size with the usual elongated or oval-shaped hole in the tie-plate, and it is usually made flat to bear against the flat face of the tie-plate, and as here shown, it has ears 30, extended from it, respectively, 70 at the top and bottom, the end-portions of which are bent to form hooks to receive the bond-wire loops. The uppermost ear is bent forward and then its end-portion is bent upward and rearward, thereby to form a recess of the bond-wire loop and to provide a space between the end of the ear and the tie-plate for the introduction of said loop and also to form a seat on which the loop rests when placed therein, as represented by full 75 lines Fig. 3. After the bond-wire loop has been placed in the recess the end-portion of the ear may be further bent rearward until it engages or nearly engages the face of the tie-plate, as represented by dotted lines 80 Fig. 3, thereby closing the entrance to the recess formed therein. The lowermost ear is bent forward and upward to form a hook to loosely receive and support the bond-wire loop, as represented by full lines Fig. 3, and 90 after the bond-wire loop has been placed in the recess of the hook the end-portion of the ear or hook is bent rearward, as represented by dotted lines Fig. 3, until it engages or nearly engages the face of the tie-plate. 95 The metal composing the annular plate is sufficiently ductile to enable its ears to be bent in this manner. Each bent ear is designed to receive a single bond-wire loop, and, as it will be observed, holds the same 100 yet permits removal whenever desired, and in case of removal it permits of the introduction of a new wire by passing the end thereof through the recess. The support admits of the bond-wire being inspected 105 quickly throughout its length.

I claim:

A bonding device for rails including a detachable plate formed with an oval shaped opening having a minimum diameter corresponding to the maximum diameter of a securing bolt which said opening is adapted 110

to receive, the upper and lower edges of the plate being formed in diametrically opposed relation with duplicate projecting strips, one of said strips being bent at an angle to the surface of the plate and outwardly therefrom and then curved upwardly and rearwardly to form a housing open toward the rear of the plate, the other of said strips being projected in the normal plane 10 of the plate and then projected outwardly and upwardly to form a housing opening

at right angles to the opening in the first mentioned housing, the said housings being designed to receive the bond wires.

In testimony whereof, I have signed my 15 name to this specification, in the presence of two subscribing witnesses.

ALFRED A. ZIEGLER.
